UNITED STATES PATENT OFFICE.

HIRAM D. LAYMAN, OF LITTLE ROCK, ARKANSAS.

LIFE-PRESERVER.

SPECIFICATION forming part of Letters Patent No. 550,226, dated November 19, 1895.

Application filed November 17, 1894. Serial No. 529,180. (No model.)

To all whom it may concern:

Be it known that I, HIRAM D. LAYMAN, a citizen of the United States, residing at Little Rock, in the county of Pulaski and State of Arkansas, have invented a new and useful Life-Preserver, of which the following is a specification.

This invention relates to life-preservers; and it has for its object to effect certain improvements in life-preservers of that class in which the entire body of the wearer is protected from the water.

To this end the main and primary object of the present invention is to provide a light, durable, and perfectly safe life-preserver that is easily applied and worn with perfect comfort, while at the same time being so constructed as to bring the body of the wearer in an upright position the moment the water is reached and to maintain the body in such position while the preserver is being propelled through the water to a point of safety.

With these and other objects in view, which will readily appear as the nature of the invention is better understood, the same consists of the novel construction, combination, and arrangement of parts hereinafter more fully described, illustrated, and claimed.

In the drawings, Figure 1 is a perspective view of a life-preserver constructed in accordance with this invention. Fig. 2 is a vertical central sectional view of the same. Fig. 3 is a horizontal sectional view on the line α α of Fig. 2.

Referring to the accompanying drawings, 1 designates a continuous tubular inflatable float-body of an oval shape, and which is provided with an interior series of air-compartments 2, with which communicate suitable 40 valved filling-pipes 3, providing means for inflating the tubular body for use or allowing the air to be pressed out of the same when not in use. The oval shape of the tubular inflatable body provides a narrow front end and a wide rear end, in order that but little resistance will be presented to the water as the preserver is propelled therethrough, while at the same time being sufficiently large to sustain the weight of a person. At the wide rear end 50 thereof the body 1 is of a greater diameter than at the narrow front end, in order that the weight of the wearer may be properly sus-

tained without affecting the horizontal floating position of the body, which is always maintained while the preserver is in the water. 55 The oval-shaped body 1 is preferably made of suitable rubber material, and encircles the upper part of a flexible water-tight pantaloons-suit 4, that is flexibly connected to the inner side edges of the said body 1 by means of the 60 flexible webbing 5, that admits of a free and easy movement for the body of the person within the suit 4 while in the water and also maintains the body 1 positively relatively disposed with respect to said pantaloons-suit. 65

The flexible webbing 5 is seamed onto the inner sides of the body 1 and the outer side of the suit 4 by water-tight seams, and diverges in separate pieces from the body 1 to the suit 4, in order that the float-body 1 may be held 70 attached to the pantaloons-suit at an oblique angle to the longitudinal center thereof or at an oblique angle to the length thereof, as clearly illustrated in Figs. 1 and 2 of the drawings. By reason of the fact that the float-body 1 is disposed at an oblique angle to the length of the suit 4, the moment the float-body reaches the water the same will bring the suit 4 to an upright position, so that it is impossible for the life-preserver to be capsized. 75

The pantaloons-suit 4 is provided at its upper opposite edges with the shoulder-straps 6, and below such straps with the body-strap 7, to provide for fastening the same securely to the body of the wearer, and the pantaloons 85 proper or leggings of the said suit are provided upon opposite sides, near the feet thereof, with the paddles 8, that provide means for propelling the life-preserver.

The pantaloons-suit 4 is connected at its rear side directly against the wide rear-end portion of the oval-shaped float-body 1, so that almost the entire weight of the wearer is placed on this end of the body, which will easily sustain the weight without tilting or capsizing, and 95 said pantaloons-suit has attached to both of the knees thereof one end of the adjusting-straps 9, the other ends of which are buckled at 10 to the front end of the body 1, so that when the wearer of the preserver becomes 100 tired of an upright position the legs may be lifted to and secured in the ordinary sitting posture, as illustrated in Fig. 2 of the drawings.

The many advantages of the herein-described life-preserver will readily suggest themselves to those skilled in the art, and the float-body of the preserver may carry a compass 11, canisters or bags 12, and such other conveniences as may be desired; and it will be understood that changes in the form, proportion, and the minor details of construction may be resorted to without departing from the principle or sacrificing any of the advantages of this invention.

Having thus described the invention, what is claimed, and desired to be secured by Letters Patent, is—

15 1. In a life preserver, a flexible water-tight pantaloons suit, a continuous tubular inflatable float body encircling the upper part of said suit and disposed at an oblique angle to the length of the suit, and positive fastening 20 means for connecting the float body with the pantaloons suit and maintaining the same relatively so disposed to each other, substantially as set forth.

25 2. In a life preserver, a continuous tubular inflatable oval float body of a greater diameter at its rear than at its front end, and a flexi-

ble pantaloons suit encircled near its upper end by said float body and connected to the same against the rear end portion thereof, substantially as set forth.

3. In a life preserver, a flexible pantaloons suit, a tubular inflatable float body encircling the upper part of said suit and disposed at an oblique angle to its length, and flexible pieces of diverging webbing connecting the inner 35 sides of the float body with said pantaloons suit, substantially as set forth.

4. In a life preserver, the flexible watertight pantaloons suit provided with propelling paddles, a float encircling the upper part of 40 said suit and attached thereto, and adjusting straps attached at one end to the knees of said suit and adjustably at their other ends to said float, substantially as set forth.

In testimony that I claim the foregoing as 45 my own, I have hereto affixed my signature in the presence of two witnesses.

HIRAM D. LAYMAN.
